(57) **CLAIM**

The ornamental design for a utility knife, as shown and described.

DESCRIPTION

FIG. 1 is a perspective view from the front above right of the invention with the blade extended;
FIG. 2 is a right-side view of the invention with the blade extended;

FIG. 3 is a front-end view of the invention;

FIG. 4 is a left-side view of the invention with the blade extended, the broken lines here and in FIGS. 6 and 7 indicating disclaimed elements;

FIG. 5 is a rear-end view of the invention;

FIG. 6 is a top view of the invention;

FIG. 7 is a bottom view of the invention;

FIG. 8 is a perspective view from the front lower right of the invention with the blade extended; and,

FIG. 9 is a view like FIG. 1 of the invention but with the blade retracted.

The broken lines depict portions of the utility knife in which the design is embodied that are not considered part of the claimed design.
